UNITED STATES PATENT OFFICE.

BENJAMIN F. AUGUSTINE, OF BUFFALO, NEW YORK.

ROTARY ENGINE.

1,238,870.

Specification of Letters Patent.

Patented Sept. 4, 1917.

Original application filed July 29, 1912, Serial No. 712,136. Divided and this application filed December 8, 1915. Serial No. 65,774.

To all whom it may concern:

Be it known that I, BENJAMIN F. AUGUSTINE, a citizen of the United States, residing at Buffalo, in the county of Erie and State 5 of New York, have invented certain new and useful Improvements in Rotary Engines, of which the following is a specification.

This invention relates to rotary engines. In my Patent 1,009,213, granted November 21, 1911, there is disclosed a rotary engine wherein is embodied a cylinder in which is mounted a piston carrier rotatable under the influence of an operating fluid, a portion of which is utilized to create an 15 opposing force on the piston carrier substantially equal to the non-rotating force of the operating fluid against the piston carrier to counterbalance the same. The cylinder contains an abutment formed to provide 20 a chamber to receive the piston carrier. The ends of the abutment are reduced and telescoped by caps secured to the piston carrier. The reduced ends of the abutment are formed to provide pockets between the abutment and caps. These pockets have 25 communication with the piston carrier chamber through ports leading from the pockets to said chamber. The portion of the operating fluid which effects a counterbalance of the 30 piston carrier passes through these ports and the said caps float or run smoothly on the fluid in the pockets.

In my application filed July 29, 1912, Serial No. 712,136, now Patent No. 1,199,229, 35 dated September 26, 1916, I disclose another type of rotary engine embodying the above and other characteristics and, among other features, I provide the type of engine disclosed in my said application with means 40 in the ports, which establish communication between the pockets and the piston carrier chamber, to prevent the leakage of fluid from the pockets back into the piston carrier chamber and it is upon said leakage 45 preventing means that the present application is based, it being a divisional application from the one filed by me on July 29, 1912.

With the above and other objects in view, 50 the present invention consists in the combination and arrangement of parts herein-after more fully described, illustrated in the accompanying drawings and particularly pointed out in the appended claims, it being understood that changes may be made in

the form, proportion, size and minor details without departing from the spirit or sacrificing any of the advantages of the invention.

In the drawings:—

Figure 1 is a transverse vertical sectional view through one type of engine, illustrating my invention, the water for cooling purposes being not shown in the rotatable member or abutment, and the section being taken on a line between one end of the engine and the external rib on the abutment.

Fig. 2 is a detail perspective view of the abutment.

Fig. 3 is a detail perspective view of one 70 of the telescoping caps.

Fig. 4 is a transverse vertical sectional view of the invention, taken through the engine at a point in line with the external rib on the abutment.

Fig. 5 is a horizontal sectional view.

Fig. 6 is a detailed view showing parts of the fluid forming and compressing valve controlling means.

Referring now more particularly to the 80 accompanying drawings it is believed unnecessary to illustrate an engine in its entirety but to illustrate only sufficient structure of the engine as will enable a clear understanding of that part of the invention 85 which it is desired to claim in this application.

The invention consists generally in providing a main engine casing consisting of a suitable supporting base 10 on which is 90 mounted a cylinder 11 which is preferably cast integral with the base. An abutment 12 is located in the cylinder and this abutment is formed to provide a chamber 13 which constitutes the cylinder proper. This abutment may have a water cooling chamber 12', the water being supplied by a pipe 12^a. The water may be withdrawn from the chamber 12' by way of a pipe 12^b, 12^c being a pipe for "priming" purposes. A 95 rotatable piston carrier 14 is eccentrically mounted in the chamber 13 on a suitable axis 15 in concentric relation to the casing cylinder 11. This piston carrier may have a water cooling chamber 18' supplied with water by the branched pipe 14^a. Radially 100 slideable pistons 16 are mounted on the carrier 14 and may be operated after the fashion illustrated in my aforesaid patents or in any suitable manner. The operating fluid 110

may be supplied to the chamber 13 for driving the piston carrier 14 in any suitable manner, as for instance, after the fashion described, illustrated and claimed in my 5 said prior patents.

The abutment 12 is formed on the outer face thereof with a central circumferentially disposed rib 17 which fits tightly within the cylinder 11. The abutment has 10 exterior cut away portions at each end adapted to receive caps 18 secured to the piston carrier 14 by means of suitable fastenings 18^b operative through the apertures 18^a in the caps. The outer face of the abutment is still further cut away at its ends so as to form a series of pockets 19 which are circumferentially arranged about the abutment and extend from a point adjacent the aforesaid central rib 17 to a point adjacent 15 the ends of the abutment. These pockets are separated by ribs 20 extending longitudinally of the abutment. The caps 18 are so proportioned as to have a smooth running fit with the ribs 20 and each has an annular 20 tongue 21 adapted to have smooth running fit in the respective annular groove 22 formed in the sides of the annular rib 17 to prevent leakage. Each cap 18 has an internal annular ring 23 adapted to run 25 smoothly on the respective outer end of the abutment adjacent the outer ends of the respective ribs 20, whereby the sides of the pockets 19 are closed by the ribs 20 and the outer ends of said pockets closed by the annular portions 23 of the caps and together 30 with the caps forming closed pockets.

The rotatable member may be driven by any suitable operating fluid, the character 40 of which is immaterial as far as the present invention is concerned. The means of introducing the operating fluid into the chamber 13 is immaterial, as is also the means of exhausting the fluid from said chamber. However, the means for supplying the operating 45 fluid to the chamber is shown as being the same as disclosed in my said Patent No. 1,199,229, dated September 26, 1916, and the operating fluid is subsequently discharged from said chamber 13 in the same 50 manner as in my prior patent, just alluded to. For instance, the main drive shaft 15 has a hollow portion which is provided with upper and lower ports 30 and 31, (Fig. 4) which are adapted to rotate into and out of 55 registration with a recess 32 in the valve member 33 located fixedly within the hollow portion of said main drive shaft 15. The hollow portion of the main drive shaft 15 has other upper and lower ports 34 and 35 60 (Fig. 4) which are adapted to be rotated into and out of registration with the recess 32 in said valve member 33 as the main drive shaft and rotatable piston carrier rotate so as to provide for the discharge of 65 fluid to the compression chambers 37 and 38.

For instance, referring to Fig. 4, and assuming that the rotatable piston carrier is in rotation, the plunger 39 in the compression chamber 38 is compressing fluid and forcing it through the port 31 and into 70 the recess 32 of the valve member 33 and through the port 35 in the hollow portion of the main drive shaft and into and through a duct 41 in the rotatable member into the chamber 13 in the rear of the piston 16 when it is exploded by means of a suitable 75 sparking device 42 connected up in any suitable manner with any suitable source of electric energy. The exploded compressed fluid expands and impinges against the piston 16, furnishing the force or impulse to rotate the rotatable member. The products of combustion pass out of the explosion chamber 13 through the exhaust ports 43 in the abutment and into the exhaust chamber 80 85 44 in the base 10 and finally out through the exhaust port 45. As the plunger 39 moves inwardly in the compression chamber 38 and thus compresses and forces the mixture into the explosion chamber 13, it will be understood that the plunger 46 in the compression chamber 37, is moving outwardly 90 in its chamber, creating a vacuum or suction for drawing a charge of fluid into such chamber through the port 36 in the valve member 33 and a port 40 (Figs. 1 and 6) in the axis 15 into the compression chamber 37, there being a duct 41' in the rotatable member for coöperation with the recess 32 in said valve member and the ports 30 and 34, in Fig. 4, to effect discharge of fluid 95 from the compression chamber 37 into the explosion chamber 13 through the duct 41'. The plungers 39 and 46 operate alternately 100 to receive the mixture and compress and force the mixture into the explosion chamber 13. Inasmuch, as the invention involved in this case is not directed to the means for supplying or exhausting the operating fluid from the engine, it would seem that further 105 explanation in this connection would be unnecessary, especially in view of the fact that this is a divisional application from that disclosed in my said Patent No. 1,199,229, dated September 26, 1916, to which reference 110 may be readily had, if necessary.

Each pocket 19 is connected with the cylindrical chamber 13 by a port 24 so that the centrifugal force acting on the operating fluid will carry the lubricant therein 115 and a certain part of the water of condensation and a portion of the pressure through said ports 24 into the pockets 19 around the outer face of the abutment. The operating fluid will create a pressure against 120 the caps 18 which are secured to the piston carrier to counterbalance the same in the manner described in my aforesaid patent 125 and said application.

By introducing a certain amount of lubri- 130

- cant into the cylinder chamber 13 the centrifugal force will carry the same out through the aforesaid ports 24 into said pockets 19 and the caps 18 will practically float on 5 the lubricant support in the pockets in the outer surface of the abutment. By this construction I form a support on which the carrier runs smoothly, even though the carrier be slightly off center.
- 10 A valve mechanism is disposed in each port 24 so as to prevent leakage of the fluid or lubricant or both from the pockets back into the chamber 13. As shown, each valve is of like construction and may consist of 15 a ball 26 held normally against its seat 27 at the inner end of the respective port by means of a suitable spring 28. The springs are supported by the removable ported plugs or bushings 29 which preferably have 20 a screw threaded fit in the outer ends of the ports 24. These spring controlled ball valves prevent the escape of fluid or lubricant or both from the pockets back into the chamber 13, sealing the latter against 25 loss of lubricant so that there is always confined within the pockets 19 a full supply of lubricant.

The operating fluid in the chamber 13 exerts its pressure against these ball valves 30 26 and immediately upon the pressure being reduced in the chamber 13 the springs 28 force the balls to their seats with the result that the pockets are full of fluid or lubricant or both flush to the balls and the 35 springs are therefore constantly in a bath of lubricant and thereby not unduly affected by the heat. Thus in the event that there is a leak between two adjacent pockets 19 when the pockets are positioned respectively on opposite sides of a radial piston so 40 that the passages leading from the pockets will connect with the high and low pressure sides of the cylinder, the valves will operate to prevent leakage through the ports 24 from the pockets to the cylinder 13. These 45 pockets 19 being constantly filled with fluid or lubricant or both, the result is that the caps 18 practically float on liquid bearings.

What is claimed is:—

- 50 1. The combination of a cylinder, an abutment in the cylinder having a cylindrical chamber therein, a rotatable piston carrier mounted in said chamber, pistons 55 slideable on the carrier, means for supplying an operating fluid to said chamber to rotate said piston carrier, caps secured to the rotatable piston carrier and telescoping with the ends of the abutment, the exterior of the abutment being constructed to provide fluid 60 receiving pockets between the caps and the abutment, the abutment having ports lead-

ing into said pockets, and valves disposed in said ports.

2. A rotary engine including in combination, an abutment having a cylindrical chamber therein, a rotatable member in said chamber, caps connected to said rotatable member and having running contact with the abutment, means for supplying an operating fluid to said chamber for operating 70 the rotatable member, said abutment having pockets formed in its outer face, and valved passages leading from the interior of the abutment to said pockets and operable to permit passage of fluid from said chamber to said pockets and to prevent escape of fluid from the pockets back into the chamber so as to provide and maintain a lubricant support upon which the caps revolve. 80

3. The combination of a cylinder, an abutment mounted in the cylinder and having a cylindrical chamber therein, a rotatable member within said chamber, means for supplying an operating fluid to said chamber to rotate the rotatable member, means for utilizing a portion of the operating fluid to create an opposing force on said rotatable member substantially equal to the non-rotating force of the operating fluid against 90 said rotatable member to counterbalance the same, and valved passages between the cylinder and the means for utilizing a portion of the operating fluid for creating the opposing force on said rotatable member. 95

4. The combination of a cylinder, an abutment in the cylinder having a cylindrical chamber therein, a rotatable piston carrier mounted in said chamber, caps connected to the carrier and telescoping with the ends of the abutment, the abutment and the caps being constructed to provide fluid receiving pockets between the caps and the abutment, and a plurality of independent valved ports establishing communication between said chamber and said pockets to permit passage of fluid from the chamber to said pockets and to prevent escape of fluid from the pockets back into the chamber. 105

5. The combination of a fixed member 110 having a cylindrical chamber therein, a rotatable member within the fixed member, means for supplying an operating fluid to said chamber to operate the rotatable member, a fluid pressure means to oppose and 115 counterbalance the non-rotating forces of the operating fluid on said rotatable member, and valved passages between the cylinder and said opposing fluid pressure means.

In testimony whereof I affix my signature.

BENJAMIN F. AUGUSTINE.
